CLAIM

The ornamental design for a speaker with lighting, as shown and described.

DESCRIPTION

1. Speaker with lighting

1.1 is a perspective view of a speaker with lighting showing our new design;

1.2 is a front elevation view thereof;

1.3 is a rear elevation view thereof;

1.4 is a left-side elevation view thereof;

1.5 is a right-side elevation view thereof;

1.6 is a top plan view thereof;

1.7 is a bottom plan view thereof; and

1.8 is a partially enlarged view of a portion of 1.1.

1 Claim, 8 Drawing Sheets
